UNITED STATES PATENT OFFICE.

FREDERICK A. MCARTHUR, OF SPRINGFIELD, MISSOURI.

DESIGN FOR AN ANGLE-COCK FOR AIR-BRAKE PIPES.

SPECIFICATION forming part of Design No. 26,441, dated December 22, 1896.

Application filed July 11, 1896. Serial No. 598,911. Term of patent 14 years.

To all whom it may concern:

Be it known that I, FREDERICK A. MCARTHUR, of Springfield, Greene county, Missouri, have invented a new and original Design for Angle-Cocks for Air-Brake Pipes, of which the following is a full, clear, and exact description, reference being had to the accompanying drawings, forming a part thereof.

My invention relates to an original design for an angle-cock for air-brake pipes, the leading feature of which consists in a cylindrical coupling elbow or arm located at an angle relative to the vertical position which the corresponding part has heretofore occupied in this class of devices.

Figure 1 of the drawings represents a side elevation of my newly-designed angle-cock. Fig. 2 represents a front view of the same, and Fig. 3 is a top plan view of the same.

1 designates the tapering or conical body portion of the angle-cock, and arranged at the rear side of the same is a cylindrical arm 2.

3 designates an elbow or arm which, instead of being directly at the front side of the body portion 1 and diametrically opposite the arm 2, as heretofore, is located at an angle to said arm 2 and projects forward and laterally from the body portion, as shown.

What I claim is—

The design for an angle-cock for air-brake pipes, substantially as herein shown and described.

In testimony whereof I affix my signature in presence of two witnesses.

FREDERICK A. MCARTHUR.

Witnesses:

THOMAS JONES,
G. Y. THORPE.
